United States Patent Office

Des. 214,781
Patented July 29, 1969

214,781

MULTISTORY BUILDING

Jovan Skocic, 2529 Lakeshore Blvd. W., Apt. 214,
Toronto 14, Ontario, Canada

Filed Aug. 15, 1968, Ser. No. 13,148

Term of patent 14 years

Int. Cl. D26—04

U.S. Cl. D13—1

FIG. 1

FIG. 3

FIG. 2

FIG. 1 is a view in perspective of a multistory building according to my invention.

FIG. 2 is a side view in elevation of the multistory building shown in FIG. 1, and

FIG. 3 is a top plan view of the multistory building shown in FIGS. 1 and 2.

I claim:

The ornamental design for a multistory building, as shown and described.
